UNITED STATES PATENT OFFICE.

VICTOR M. FOWLER, OF SPOKANE, WASHINGTON.

BRACKET.

Application filed October 17, 1925. Serial No. 63,050.

The invention contemplates the use of a pair of spaced and adjustable supporting arms or brackets, and a brace or strut for engagement against a building wall beneath the window sill, to support the arms in proper adjusted position, and the invention consists in certain novel combinations and arrangements of parts in connection with these parts as will hereinafter be more fully set forth and claimed.

In the accompanying drawings I have illustrated one complete example and a slight modification of the physical embodiment of my invention wherein the parts are combined and arranged according to the best modes I have thus far devised for the practical application of the principles of my invention.

Figure 1 is a perspective view of the bracket showing in dotted lines a portion of a window frame and a window sill, together with a shelf, to illustrate the general arrangement of parts.

Figure 2 is an enlarged detail sectional view transversely of a portion of the shelf, showing the retaining device between one of the bracket arms and the shelf.

Figure 3 is an enlarged detail sectional view of one of the bracket arms showing a cushion thereon for the shelf.

Figure 4 is a perspective view of a slightly modified form of bracket arm.

In order that the general assembly and arrangement of parts may readily be understood I have illustrated in Figure 1, in dotted lines a portion of a window frame F and the window sill S, it being understood that the bracket is detachably supported at the exterior of the window from the sill and against the wall of the building below the sill.

The bracket is preferably made up of metal and is adjustable to suit various widths of windows, a pair of spaced supporting hooks 1 and 2 forming part of the equipment. These hooks are secured as by threads in the window sill at the desired spaced locations and the bracket as a whole is supported therefrom in a detachable manner.

Two spaced bracket arms indicated as a whole by the numerals 3 and 4 are used, each of which is provided with a perforated lug 5 at its end to slip over one of the hooks as indicated in Figure 1. At their outer ends 55 the bracket arms are fashioned with in-turned hooks 6 which form an angular space

for each arm. In Figures 2 and 3 it will be seen the arms are preferably provided with upper beaded edges 7 and a reinforcing or strengthening web 8, the rounded bead or edge 7 being designed to receive and retain a cushion or filler 9. This cushion may be formed by slitting a suitable length of rubber hose or other tubular article of a size to fit over the beaded edge 7, which will frictionally engage the bead and be retained thereon as indicated in Figure 3.

At the underside of each hook 6 in the space at the end of the arm a retaining spring 10 is located and secured to the hook member as by a rivet 11.

The rectangular shelf indicated as 12 is preferably of wood but may be of other material, and is designed to rest upon the tops of the two spaced bracket arms, in contact with the cushion 9 on the beaded edges of the arms. The outer edge of the shelf is slipped under the hooks 6 into the space provided therefor at the end of the bracket arms, into frictional contact with the two retaining springs, and the latter hold the shelf in contact with the cushions in such manner as to prevent lateral displacement of the shelf. Outward movement of the shelf away from the window is prevented by the hooks 6. The shelf is thus retained in rigid position on top of the bracket arms by means of the retaining springs on the hooks and the cushion or filler 9 on the beaded edges of the arms.

In connection with the supporting hooks 1 and 2 the bracket is also supported and braced from beneath by a strut which is adjustable or extensible with the bracket arms for adaptation to various width of windows or supports.

The strut is of U-shape and comprises a pair of telescopic bars 13 and 14, the latter being tubular to receive the end of the former, and each bar is fashioned with a right angle arm 15. These arms are connected by a pair of telescopic brace rods 16 and 17, the latter being tubular to receive the former, and the whole brace is adapted to form a support, as for instance a towel rack, if desire.

The free ends of the arms 15 are bent or twisted to form pawls 18 that are adapted to engage a pair of selected rack teeth 19 fashioned in the under edge of the web 8 of each arm. By means of the strut the bracket arms and shelf may be adjusted in horizon-

tal position and there held for the performance of their usual functions.

The strut which has its bars 13 and 14 in contact with the wall of the building as 5 a support is suspended from the bracket arms by means of a pair of pivoted links 20 with pivotal connections 21 and 22 to the strut arms 15 and bracket arms 3 and 4 respectively.

10 The strut by means of this three point suspension at each end of the bracket thus forms a rigid bracket structure for the support of the shelf 12 and in connection with the hooks 1 and 2 the whole combination of 15 parts is retained in detachable position at the exterior of the window.

In the modified structure of Figure 4 the hooks 1 and 2 are employed in connection with the perforated lug 5 at the end of the 20 bracket arm 23, which arm at its outer end is provided with a retaining hook 24 for the shelf.

A pair of spaced struts or braces 25 are here employed each made up of a pair of 25 metal straps having oppositely extending feet 26 to engage the building wall beneath the bracket arms. The braces 25 are

pivotaly connected with the bracket arms by means of links 27 and a pin 28 at the outer end of each brace is used to engage a 30 selected notch, or rack tooth 29 in the under edge of the bracket arm.

Having thus fully described my invention what I claim as new and desire to secure by Letters Patent is—

35 1. The combination with a pair of spaced detachable bracket arms having an extensible supporting strut and pivotal links between said strut and arms, said arms having beaded edges, tubular cushion members on 40 said edges, hooks at the free ends of said arms, and retaining springs carried by said hooks for engagement with a shelf.

2. The combination of a pair of spaced 45 detachable bracket arms having end hooks, beaded edges and rack teeth, of an extensible strut having pawls to engage said teeth, an extensible rack-rod connecting said strut, pivoted links between the strut and said arms, cushions on said beaded edges, 50 and retaining springs secured to said hooks.

In testimony whereof I affix my signature.

VICTOR M. FOWLER.
